UNITED STATES PATENT OFFICE.

OLIVIER LAROCHE AND MARTIN L. N. TUCKER, OF LOWELL, MASSACHUSETTS, ASSIGNORS TO LAWRENCE MANUFACTURING COMPANY, OF LOWELL, MASSACHUSETTS, A CORPORATION OF MASSACHUSETTS.

KNITTING-MACHINE.

1,082,881.

Specification of Letters Patent.

Patented Dec. 30, 1913.

Application filed May 25, 1911. Serial No. 629,251.

To all whom it may concern:

Be it known that we, OLIVIER LAROCHE, a subject of the King of Great Britain, and MARTIN L. N. TUCKER, a citizen of the United States, residing at Lowell, in the county of Middlesex and State of Massachusetts, have invented certain new and useful Improvements in Knitting-Machines; and we do hereby declare the following to be a full, clear, and exact description of the invention, such as will enable others skilled in the art to which it appertains to make and use the same.

The invention relates to circular spring needle knitting machines, and more especially to mechanism for knitting open mesh fabric on this type of machine.

The object of the invention is to provide a novel and improved construction of stitch forming and stitch transferring mechanism whereby stitches may be transferred from one needle to another with certainty, and with a minimum strain upon the fabric and needles, and whereby a novel and improved fabric is produced.

To these ends the invention consists in the features of construction and combinations of parts hereinafter described and set forth in the claims.

90 The various features of the invention will be readily understood from an inspection of the accompanying drawings, and the following detailed description of the mechanism illustrated therein.

95 In the drawings, Figure 1 is a plan view of so much of a knitting machine as is necessary to illustrate the application of the present improvements thereto; Fig. 2 is a vertical sectional detail showing the stitch transferring devices; Figs. 3, 4 and 5 are sectional details illustrating the construction of the stitch wheel; Fig. 6 is an enlarged view showing the manner in which the stitch is transferred from one needle to another; Fig. 7 is a sectional detail showing the needle gathering and alining wheel and the coöperating presser disk; Fig. 8 is a vertical sectional view showing the devices for throwing one of the presser disks out of operation; Fig. 9 is a sectional elevation showing the stop mechanism and devices for throwing the presser disk out of operation; and Figs. 10 and 11 are detail views showing parts of the stop mechanism.

In the drawings the invention is illustrated as embodied in a spring needle machine such as is used for knitting tubular fabric from which underwear is manufactured. This machine is the same in construction and mode of operation as well-known machines in common use, except so far as the construction is modified by the embodiment of the present improvements therein. The machine is provided with the usual, plurality of feeds and stitch forming and cast-off devices, which are not shown in the drawings. The spring needles 1 are carried in the usual cylinder 2 which is continuously rotated during the operation of the machine through the usual driving mechanism. In addition to the feeds and stitch forming devices of the usual construction, the machine is provided with a novel form of stitch transferring mechanism for transferring stitches from certain needles to the next adjacent needles, and is also provided with a novel construction of stitch forming devices for the feed immediately preceding the stitch transferring mechanism.

The stitch transferring mechanism comprises a needle gathering and alining wheel 3 provided with teeth spaced to receive two needles between them. Each tooth comprises two spurs 4 embracing a needle alining slot 5 adapted to receive two adjacent needles and bring them into alinement one back of the other. The ends of the spurs are beveled at 6 to form a flaring mouth at the end of the slot which directs the needles into the slot. The wheel is driven by the engagement of the needles with the teeth, and as it rotates the teeth divide the needles into series of four. Every third needle *a* enters a slot 5, and every fourth needle *b* is engaged by the spur 4 at the rear of the slot and is forced inward and directed into the slot back of the needle *a*, as indicated in Fig. 7. After the needles *a* *b* have been thus brought into alinement one back of the other, the stitch on the needle *a* is forced down over the needle *b* by a push-down plate 7 which engages the fabric and forces it down along the needles, as indicated in Fig. 2, so that the stitch on the needle *a* passes down over both the needles *a* and *b*. In order that the needles may lie close together within the slot 5, when the stitch on needle *a* is forced down

over the needle *b*, so that the proper engagement of the stitch with the needle may be insured, a presser is provided for engaging the back of the rear needle *b* and holding it against the pull of the fabric. In the construction shown this presser consists of a disk 8 mounted to turn freely about its pivot, and arranged to engage the needle to which the stitch is to be transferred at the point where the push-down plate 7 acts to force the stitch on the needle *a* down over the top of the needle *b*. After the needles pass from engagement with the teeth of the wheel 3, the stitch which was on needle *a* is on both the needle *a* and the needle *b*. During the continued rotation of the needle cylinder this stitch is cast off of the needle *a* and thus its transfer from the needle *a* to the needle *b* is completed. The means for casting off the stitch consists of a presser disk 9 provided with teeth 10 arranged to engage and close the beards of the needles *a*, and a coöperating landing wheel 11 which slides the stitch up over the beard and casts it off.

The needle *a* from which the stitch is transferred is in advance of the needle *b* to which the stitch is to be transferred, and the stitch leading from the needle *a* tends to occupy a position which is inclined forward away from the needle *b*. In order to draw the fabric back and bring the stitch on the needle *a* into proper position above the needle *b* a retarding device in the form of a fixed plate 12 is arranged to bear upon the inside of the fabric to the rear of the point of transfer. This retarder puts a drag upon the fabric, and draws it back at the point of transfer sufficiently to insure the proper engagement of the needle *b* with the stitch carried by the needle *a* when the stitch is forced down over the needles. It is also preferred to provide a tension wheel 13 arranged to engage the outer side of the fabric above the point of transfer, which will act to put an increased tension on the fabric and thus insure the drawing tant of the loops at the point of transfer.

In order that the loop or stitch may be transferred from one needle to the other without putting undue strain upon the yarn, it is desirable that the loop which is transferred be a comparatively long loop. To provide a loop of this character, and also to further minimize the strain upon the loop, the stitch forming mechanism for the feed immediately preceding the stitch transferring mechanism is so constructed that it does not form a loop upon the needle from which the stitch is to be transferred, and does not cast off from this needle the loop or stitch from the preceding feed. The result is that the needles from which the stitches are to be transferred carry loops in the course of stitches preceding the course

of stitches carried by the needles to which the stitches are to be transferred. In the construction shown, the stitch forming mechanism for the feed next preceding the stitch transferring mechanism comprises a stitch wheel 14 provided between every third and fourth blade with a beard engaging surface 15 which engage and close the beards of the needles *a* from which the stitch is to be transferred. The yarn acted upon by the stitch wheel is therefore carried up by the wheel over the beards of these needles, instead of being carried up under the beards. No yarn is therefore delivered to the needles *a* by the stitch wheel. The yarn delivered by the stitch wheel to the other needles is measured and distributed between the needles by a dividing wheel 16 of usual construction. The stitch wheel and dividing wheel are so constructed that the loops formed are somewhat longer than the loops formed by the stitch wheels for the other feeds. The presser disk 17 which closes the beards of the needles and cooperates with the landing wheel 18 in casting off the loops carried by the needles is provided with a series of recesses 19 adapted to register with the needles *a* so that the beards of these needles are not closed and the loops on the needles are not cast off. Thus the stitch forming devices immediately preceding the stitch transferring mechanism are constructed to skip the needles from which the stitches are to be transferred so that new loops are not formed on these needles, and the needles retain the loops formed by the stitch forming devices of the next preceding feed. These loops are transferred to the needles *b* by the stitch transferring mechanism, so that each needle *b* after the needles have passed the stitch transferring mechanism carries a stitch of the course formed by the stitch forming mechanism of the feed next preceding the stitch transferring mechanism, and a stitch of the course formed by the stitch forming devices of the next preceding feed, as indicated in Fig. 6.

The stitch wheel 14 and the presser disk 17 are rotated by their engagement with the needles, and they must rotate in proper timed relation with each other in order that the loops on the needles which are skipped by the stitch wheel may not be cast off. If they should get out of timed relation, the stitches on these needles would be cast off, thus dropping the stitches and forming holes in the fabric. The presence of bunches or inequalities in the size of yarn may sometimes cause the stitch wheel 14 to jump away from the needles when the bunch or imperfection in the yarn is passing between a beard closing surface 15 and a needle *a*. When this occurs, the wheel 14 may not re-engage the needles in proper timed relation with the presser disk 17. In order that the

machine may be automatically stopped in such cases, a stop mechanism is provided which is controlled by a fabric engaging finger 20. This finger is arranged to ride 5 on the fabric close to the needles, and will drop through any holes formed by dropped stitches. The finger is pivoted in a sleeve 21 secured to the end of an arm 22 which projects radially from a rock shaft 23. The 10 finger is held in normal position in the sleeve by a spring pressed latch pin 24. The rock shaft is forced in a direction to press the finger 20 against the fabric by a spring 25 secured to an arm 26 projecting from the 15 shaft. The rock shaft also carries a depending arm 27 arranged to engage and operate the latch 28 of the stop mechanism. The latch 28 is provided at its forward end with a hook 29 which engages the vertical arm 20 of a bell crank lever 30. The other arm of the bell crank lever is pivotally connected to the rear end of a lever 31, the front end of which carries a lug 32 arranged to engage and hold down a spring pressed pin 33. The lower end of the pin 33 is arranged 25 to engage one side of the clutch shifting lever 34 and hold the driving clutch in engagement against the tension of the spring 35. A spring 36 engages the latch 28 and 30 holds it normally in position to engage the bell crank lever 30. If a hole is formed in the fabric by the dropping of stitches or otherwise, the finger 20 enters the hole and is moved toward the left in Fig. 11 by the 35 forward movement of the fabric. This swings the finger about its pivot, and allows the shaft 23 to rock in a direction to disengage the latch 28 from the bell crank lever 30. The spring pin 33 immediately rises 40 and releases the clutch shifting lever so that the driving mechanism is thrown out of operation.

When the driving mechanism is thrown out of operation, the momentum of the parts 45 may cause the needle cylinder to travel forward until the imperfect fabric passes the presser disk 9. If this should occur, the presser disk and landing wheel 11 will act to cast off additional loops, and since the 50 stitch forming devices preceding the stitch transferring mechanism were out of time, this will cause the dropping of additional stitches. The dropping of the additional stitches is liable to so weaken the fabric 55 that it will tear away from the needles, with a resulting increase in the waste of fabric. To avoid this, means is provided for throwing the presser disk 9 out of action when the controller finger 20 detects an imperfection 60 in the fabric. As shown, this means comprises a lever 37, one end of which underlies the disk 9, and the other end of which is supported upon the end of a slide 38. A spring 39 is connected with the lever 37, and 65 tends to swing it in a direction to lift the

disk 9 out of active position. The slide 38 is provided with a notch 40, and the slide is forced in a direction to bring the notch 40 under the end of the lever 37 by a spring 41. The slide is held in position against the 70 tension of the spring 41 by engagement with the bell crank lever 30, as indicated in Figs. 1 and 9. When the bell crank lever 30 is released, as by the rocking of the controller shaft 23, the spring 41 moves the slide 38 toward the right in Fig. 10, bringing the notch 40 under the end of the lever 37, so that the spring 39 acts to rock the lever and lift the presser disk 9 out of active position. 75

While it is preferred to employ the specific construction and arrangement of parts shown and described, this construction and arrangement is not essential except so far as specified in the claims, and may be varied 80 and modified without departing from the invention. 85

Having explained the nature and object of the invention, and specifically described one form of mechanism in which it may be 90 embodied, what we claim is:—

1. A knitting machine, having, in combination, a needle cylinder provided with needles, a wheel outside the needles provided with slotted teeth arranged to pass 95 between the needles and to direct two adjacent needles into the slot one back of the other, means for forcing the stitch on the front needle down over both needles, and a presser for holding the needles against the 100 pull of the fabric, substantially as described.

2. A knitting machine, having, in combination, a needle cylinder provided with needles, a wheel outside the needles provided with slotted teeth arranged to pass 105 between the needles and to direct two adjacent needles into the slot one back of the other, means for forcing the stitch on the front needle down over both needles, and a presser engaging the back of the rear needle, 110 substantially as described.

3. A knitting machine, having, in combination, a needle cylinder provided with needles, a wheel outside the needles provided with slotted teeth arranged to pass 115 between the needles and to direct two adjacent needles into the slot one back of the other, means for forcing the stitch on the front needle down over both needles, and a rotary presser disk engaging the rear needle 120 to press the needles together in the slot, substantially as described.

4. A knitting machine, having, in combination, a needle cylinder provided with needles, a wheel outside the needles provided with slotted teeth arranged to pass 125 between the needles and to direct two adjacent needles into the slot one back of the other, means for forcing the stitch on the front needle down over both needles, and a 130

retarder engaging the fabric to the rear of the point of transfer, substantially as described.

5. A knitting machine, having, in combination, a needle cylinder provided with needles, a wheel outside the needles provided with slotted teeth arranged to pass between the needles and to direct two adjacent needles into the slot one back of the other, 10 means for forcing the stitch on the front needle down over both needles, a presser engaging the back of the rear needle, and a retarder engaging the fabric to the rear of the point of transfer, substantially as described.

15. 6. A knitting machine, having, in com-

bination, a needle cylinder provided with needles, a wheel outside the needles provided with slotted teeth arranged to pass between the needles and to direct two adjacent needles into the slot one back of the other, 20 means for forcing the stitch on the front needle down over both needles, a presser engaging the back of the rear needle, and a tension wheel engaging the outside of 25 the fabric above the point of transfer, substantially as described.
